(57) **CLAIM**

We claim the ornamental design for a food and beverage container, as shown and described.

DESCRIPTION

FIG. 1 is a top and left side perspective view of a food and beverage container in accordance with a first embodiment of my new design;

FIG. 2 is a top and right side perspective view thereof;

FIG. 3 is a right side elevational view thereof, the left side elevational view being a mirror image thereof;

FIG. 4 is a rear elevational view thereof;

FIG. 5 is a front elevational view thereof;

FIG. 6 is a bottom plan view thereof;

FIG. 7 is a top plan view thereof;

FIG. 8 is a top and right side exploded perspective view thereof;

FIG. 9 is a top and left side exploded perspective view thereof;

FIG. 10 is a bottom and right side exploded perspective view thereof;

FIG. 11 is a top and left side perspective view of the outer lid portion with the rest of the container removed for clarity of reference;

FIG. 12 is a bottom and left side perspective view of FIG. 11;

FIG. 13 is a top plan view of FIG. 11;

FIG. 14 is a bottom plan view of FIG. 11;

FIG. 15 is a vertical cross-sectional view showing a section taken along line 15-15 of FIG. 13;

FIG. 16 is a top and right side perspective view of the inner lid portion with the rest of the container removed for clarity of disclosure;

FIG. 17 is a bottom and left side perspective view of FIG. 16;

FIG. 18 is a top plan view of FIG. 16;

FIG. 19 is a bottom plan view of FIG. 16;

FIG. 20 is a top and left side perspective view of a food and beverage container in accordance with a second embodiment of my new design;

FIG. 21 is a top and right side perspective view thereof;

FIG. 22 is a right side elevational view thereof, the left side elevational view being a mirror image thereof;

FIG. 23 is a rear elevational view thereof;

FIG. 24 is a front elevational view thereof;

FIG. 25 is a bottom plan view thereof;

(Continued)

FIG. 26 is a top plan view thereof;
 FIG. 27 is a top and right side exploded perspective view thereof;
 FIG. 28 is a top and left side exploded perspective view thereof;
 FIG. 29 is a bottom and right side exploded perspective view thereof;
 FIG. 30 is a top and left side perspective view of the outer lid portion of the second embodiment of the food and beverage container with the rest of the container removed for clarity of disclosure;
 FIG. 31 is a bottom and left side perspective view thereof;
 FIG. 32 is a top plan view thereof;
 FIG. 33 is a bottom plan view thereof;
 FIG. 34 is a top and right side perspective view of the inner lid portion of the second embodiment of the food and beverage container with the rest of the container removed for clarity of disclosure;
 FIG. 35 is a bottom and left side perspective view thereof;
 FIG. 36 is a top plan view thereof; and,
 FIG. 37 is a bottom plan view thereof.
 The broken lines of the food and beverage container represent portions of the food and beverage container that do not form a part of the claimed design.
